[57] CLAIM

The ornamental design for a microcuvette assembly,
substantially as shown and described.

DESCRIPTION

FIG. 1 is an exploded perspective view of a microcuvette assembly showing our new design, the details of three of the microcuvette units being omitted for convenience of illustration;

FIG. 2 is a top plan view of the microcuvette assembly with all four units in the frame;

FIG. 3 is a side elevational view of the microcuvette assembly;

FIG. 4 is a bottom plan view of the microcuvette assembly.

FIG. I

FIG.2

FIG.3

FIG. 4
